CLAIM

The ornamental design for a display screen or portion thereof with animated graphical user interface, as shown and described.

DESCRIPTION

FIG. 1 is a front view of the first image in a sequence for a display screen or portion thereof with animated graphical user interface, according to a first embodiment;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the first image in a sequence for a display screen or portion thereof with animated graphical user interface, according to a second embodiment;

FIG. 7 is a front view of the second image thereof;

FIG. 8 is a front view of the third image thereof;

FIG. 9 is a front view of the fourth image thereof; and,

FIG. 10 is a front view of the fifth image thereof.

The appearance of the graphical user interface transitions sequentially between the images shown in FIGS. 1-5 and FIGS. 6-10. The process or period in which an image transitions to another forms no part of the claimed design. The broken line showing of the display screen or portion thereof, text and graphical features forms no part of the claimed design.
